United States Patent Office

Des. 189,730
Patented Feb. 7, 1961

189,730

CARAFE

Thomas E. Williams, Long Beach, and Jack H. Hofstetter, Orange, Calif., assignors to Purex Corporation, Ltd., South Gate, Calif., a corporation of California

Filed Apr. 8, 1960, Ser. No. 60,108

Term of patent 14 years

(Cl. D58—8)

Fig. 3.

Fig. 2.

Fig. 1 is a side elevational view of a carafe embodying our new design;

Fig. 2 is a top plan view of Fig. 1; and

Fig. 3 is a cross section on line 3—3 of Fig. 1.

The side not shown is the same as the side shown.

We claim:

The ornamental design for a carafe, substantially as shown and described.
